CROSSING PROTECTIVE SYSTEM

James Moore Evans, Detroit, Mich., assignor to
Grade Crossing Guard Corp., Memphis, Tenn.,
a corporation of Tennessee

Application October 29, 1936, Serial No. 108,150

4 Claims. (Cl. 177—329)

The present invention relates generally to signal systems for crossing protective devices, and in particular provides an improved warning light system for a crossing protective device of the projectable and retractable barrier type.

The co-pending application of the present applicant, Serial No. 108,149, filed October 29, 1936, now Patent No. 2,164,610, and assigned to the assignee of the present application, discloses and claims certain features of an improved barrier type protective system for railway, highway, or other crossings. For the purposes of the present description, the co-pending construction comprises generally a plurality of barriers, located at opposite sides of the crossing to be protected, and suitably imbedded in the roadway surface. The barriers normally occupy retracted positions in which the surfaces thereof are flush with the roadway surfaces, and are adapted to be projected a predetermined distance above the surface of the roadway to present positive barriers by which vehicles may be brought to rest and prevented from entering the protected crossing.

In the specific form illustrated, the present invention is directed to the provision of an improved warning light system for the barriers disclosed in the above identified co-pending application. As will be appreciated from a complete understanding of the present invention, however, certain features thereof are applicable to barriers of constructions other than the construction of the co-pending application, and are also applicable to protective devices of other than the barrier type. The illustration of the present invention, accordingly, in connection with a specific form of barrier, and as embodied in specific forms, is to be regarded in an illustrative and not in a limiting sense, and the term "barrier" as used in the following description and in the claims is intended, except where the context requires otherwise, to generically refer to movable protective devices positioned to obstruct or similarly impede the passage of traffic.

Objects of the present invention are to provide an improved warning light or other signal system for a crossing protective system; to provide in a crossing protective system, embodying barriers of the projectable and retractable type, a warning light and signal system including signal elements carried by the barriers; to provide a system as just stated including a plurality of light transmitting elements positioned in distributed relation along a face of a barrier, and adapted to transmit light from a source positioned within each barrier device along a roadway in the direction of

approaching traffic; to provide such a system embodying one or more stationary light sources associated with the light transmitting signal elements and one or more reflecting elements to reflect light from the light sources onto the lenses.

Further objects of the present invention are to provide a system of the above stated character, in which the lenses, reflecting elements, and light sources are so related that as the barriers rise, the beams of light are directed along the roadway at a substantially constant angle to the roadway; to provide such a system in which the reflectors move angularly relatively to the lenses and the light sources during barrier movements to thereby compensate for the relative movements between the light sources and the lenses; and to provide such a system in which the reflectors are pivotally carried by the barriers, and are provided with actuating means responsive to the barrier movements to vary the angular positions of the reflectors.

Further objects of the present invention are to provide a signal control system for a barrier type protective system, including elements responsive to the arrival of a vehicle within a predetermined distance of the crossing to be protected, for actuating the warning lights associated with the barriers; to provide such a system embodying flasher elements to provide an intermittent alternate lighting of a plurality of lamps associated with each barrier; and to provide such a system including elements responsive to the barrier movements and connected to control the lamps jointly with the vehicle controlled elements, to thereby insure correct signal operation.

With the above and other objects in view which appear in the following description and in the appended claims, preferred but illustrative embodiments of the invention are shown in the accompanying drawings, throughout the several views of which corresponding reference characters are used to designate corresponding parts and in which:

Figures 1 and 2, taken together, with Fig. 2 considered as placed to the right of Fig. 1, constitute a view in perspective of a barrier device of the type with which the lighting and signal systems of the present invention are preferably utilized;

Fig. 1A is a detail view of a controller element; 50
Fig. 3 is a view in vertical, transverse section, taken along the line 3—3 of Fig. 1;

Fig. 4 is a fragmentary view in elevation, taken along the line 4—4 of Fig. 3;

Fig. 5 is a view in transverse section through a 55

barrier, showing a modified embodiment of the present invention;

Fig. 6 is a view in elevation, taken along the line 6—6 of Fig. 5;

5 Fig. 6A is a sectional view taken on the line 6A—6A of Fig. 5;

Fig. 7 is a fragmentary view of a further modification of the present invention;

10 Fig. 8 is a schematic diagram of a preferred arrangement of track control circuits which may be used in the practice of the present invention in connection with railroad crossings; and,

15 Fig. 9 is a schematic diagram of the lighting control circuit of the present invention which is applicable to the various specific embodiments thereof shown in the above identified figures.

Referring first to Figs. 1 and 2, for an understanding of the general features of the barrier construction of the above identified co-pending 20 application, each barrier 20 is of a shell-like form, generally triangular in vertical transverse section, having a top surface and a generally arcuately formed forward or impact surface 22. Each barrier 20 is resiliently hinged at its rear corner 25 to the rear wall of an associated casing member 24, adjacent the upper edge thereof. Each casing 24 is suitably imbedded in a pit formed in the associated roadway. In the retracted position of each barrier, (Fig. 3) the top surface thereof lies 30 substantially flush with the top of the associated casing and with the associated roadway and consequently forms a continuation of the latter, over which vehicles may pass without obstruction. In the illustrated projected position, the forward 35 face of each barrier, including the impact portion and the skirt portion, is raised a substantial distance above the surface of the roadway, and constitutes a positive barrier, which, upon being engaged by the wheels of an approaching vehicle, serves to forcibly bring the vehicle to rest and prevent its passing into the crossing with which the barrier is associated. The impact portion 22 of each barrier is preferably reversely bent in relation to the skirt portion 23, the inclination and height of the impact portion above a roadway being so related that vehicles striking the barriers are brought to rest without injury to the occupants thereof. The particular formation of the barrier to accomplish this purpose 40 is disclosed and claimed in the co-pending application of Edward S. Evans, Serial No. 33,037, filed July 25, 1935, on which Patent No. 2,075,892 was granted April 6, 1937, and assigned to the same assignee as the present application.

55 A complete installation of the barrier devices, as shown in the schematic diagram, Fig. 8, preferably comprises at least two barriers 20 at each side of the crossing to be constructed, those at each side being arranged in end to end relation, and disposed for control by a single drive unit 26. Each drive unit 26, as better shown in Fig. 1, 60 comprises generally a combined motor and brake unit 28, connected through a flywheel sprocket 30 and a flexible coupling 32, to the crankshaft 34 of the adjacent barrier 20. The other end of the just mentioned crank shaft 34 is coupled as by a coupling similar to coupling 32, to the crankshaft of the immediately adjacent barrier 20. Each crankshaft 34 is connected to its associated barrier 20 through a plurality of connecting arms. The connection between each crankshaft and connecting arm 36 is of a lost motion type, so arranged that movement of the crankshaft in a barrier retracting direction positively 65 pulls the associated barrier down, through the

associated arm 36. The raising movement is effected through a plurality of torsion springs 38, one end of each of which is connected to the associated casing 24, and the other end of each of which is connected to the associated barrier through an arm 40. During a raising movement, the crankshaft motion permits the barrier to be lifted through the force supplied by the torsion springs 38. The lost motion connection between the crankshaft and the associated arm permits the barrier to be retracted against the force of the torsion springs, as by the passage thereover of a vehicle, independently of the rotative position of the associated crankshaft. The barriers associated with outgoing traffic lanes are preferably retractable in the just stated manner at any stage of their movement. The barriers associated with the oncoming traffic lanes are, however, preferably provided with locking arms 42, which become effective when the barrier reaches the 20 fully raised position to mechanically lock it in such position and prevent the just mentioned depressing movement.

25 The drive unit 26 and the control system associated therewith, which form the subject matter of a separate copending application of the present applicant, Serial No. 109,941, filed November 9, 1936, and assigned to the same assignee of the present application, is such that upon the approach of a train or other vehicle to 30 the crossing to be protected, the drive unit starts in operation, and permits the barrier to rise to an intermediate or warning position, at which time it is temporarily stopped. The warning height is preferably just sufficient to expose the herein- 35 after described signal elements associated with the barrier. After the predetermined interval, the barrier movements are continued until the barriers reach their fully projected positions, in which positions they are retained until the 40 passage past the intersection of the vehicle or vehicles which initiated their movement.

45 Considering now the elements of the system to which the present application is particularly directed, and referring to Figures 3 and 4, as well as to Figures 1 and 2, the forward face of each barrier is provided with a plurality of cut-outs 50, one thereof being illustrated as positioned adjacent one end of the barrier and another thereof as positioned adjacent the other end of each barrier. Each cut-out 50 is provided with a refracting lens 52, the outer face of which is planar and the inner face of which is provided with a plurality of horizontally extending serrations 54 which impart refracting characteristics 55 thereto. Each lens 52, preferably circular in section and of a suitable color such as red, is seated against an anular shoulder 56 formed in an inwardly extending collar 58, formed in the associated barrier face. Each lens is preferably 60 permanently bonded, as by cementing, within the associated collar.

65 The forward face of each barrier is also preferably provided with a plurality of cut-outs, arranged to define letters, and each such cut-out is preferably provided with a reflecting bull's-eye lens, such as 60. The letters thus defined spell out suitable information, the illustrated arrangement including two pairs of the letter "R," and the word "Stop." As will be appreciated, 70 the light of approaching vehicles is reflected by the bull's-eyes.

75 Light for the lenses 52 is supplied by a plurality of stationary lamp units 62, the attaching nipple 64 of each of which is secured to a conduit 76

box 66, included in a conduit line 68 which extends along the base of the associated casing 24. The direct beam from each lamp 62 is received by a reflector 70 individual thereto, and is directed thereby to the associated lens 54. Each lamp 62, reflector 70 and lens 52 thus constitute a light transmitting system, disposed to direct a beam of light along the associated roadway in the direction of approach of oncoming vehicles.

Lugs 71 at each side of each reflector 70 are pivotally supported on pins 72, which are journaled in arms 74, which depend from the upper surface of the associated barrier 20. The right-hand lug 71, as viewed in Fig. 4, is extended to provide a cam track 76, which receives a pin 78 carried at the end of a bracket 80, the right-hand end of which is secured to the barrier casing 24 by studs 82.

With this arrangement, as will be appreciated, a raising or lowering movement of the barrier 20, which occurs about a center 84 as an axis, is accompanied by a corresponding tilting of each reflector 70 about the pins 72, as an axis. The angle between each reflector 70 and the beams from the associated light 62 is a minimum when the barrier is in the retracted position, as appears clearly in Fig. 3, and this angle is gradually increased as the barrier is projected. The swinging of each reflector 70 relative to its light source 62 is accompanied by a corresponding tilting of the associated lens 52 relative to the light source. The tilting of the reflectors is so related to the tilting of the lenses, that throughout the raising and lowering movements of each barrier, the substantially uniform beams of light from the light sources, refracted by the lenses, remain at a substantially uniform angle, preferably of the order of a one degree rising angle, to the roadway. Accordingly, from the time during the initial movement of each barrier that the associated lenses 52 become exposed above the roadway, an intense beam of light is projected along the roadway at a slightly rising angle. The warning lights thus provided by the barrier are initially visible at a substantial distance from the barrier and remain brilliantly visible as the barrier is approached.

It will be noticed that in the retracted position of the barrier, shown in Fig. 3, the lens 52 is positioned slightly below the axis 84 of the pivotal movement of the barrier. The initial barrier elevating movement therefore causes the lens to have a horizontal component of movement to the left (Fig. 3) relative to the lamp 62. This leftward component of movement continues until the lens 52 is elevated to the level of the axis 84, after which continued elevating movement of the lens 52 imparts to it a rightward horizontal component of movement relative to the lamp. In order to compensate for the just-mentioned reversal in direction of the horizontal components of movement of the lens 52 relative to the lamp 62, the curvature of the initially active portion of the cam track 76 is slightly angularly deflected from the main portion thereof, the joinder between the two portions being indicated at 76a.

In the modified embodiment of Figs. 5, 6 and 6A, the general arrangement is as described with reference to the preceding figures and corresponding reference characters are used to designate the corresponding parts. In this instance, two reflecting members are utilized. One of these, designated 100, is stationary with respect

to the associated barrier 20, and is secured thereto by a plurality of studs 102. The other reflecting member 104 is provided with lugs 106, by which, through pins 108, it is pivotally connected to the associated barrier 20 in a manner 5 similar to that described with reference to Figs. 3 and 4. The pins 108 are journaled in arms 110, which depend from the barrier's upper surface. In the fully raised position of the barrier, each reflector 104 is disposed parallel and in 10 flush relation to the adjacent stationary reflector 100, and thus acts as a continuation of the latter.

To effect the tilting of each of the movable reflectors 104, each thereof is provided with a 15 pinion engaging rack 112, which continuously engages a drive pinion 114. Each reflector 104 is connected to the associated rack 112 through an intermediate link 116, pivotally connected at one end to the associated reflector by a pin 20 118 and correspondingly connected to the associated rack by a pin 120.

Each rack 112 is guided in a guide member 122, and is restrained thereby against movement out of meshing relation to the drive pinion 114. 25 Each guide 122 is secured, by studs 123, to the spaced brackets 126 which project outwardly from the wall of the barrier 24. The drive pinion 114 is rotatably supported upon a trunnion 124, the opposite ends of which are journaled in the brackets 126. Brackets 126 are secured to the rear face of the barrier casing 24 by studs 130.

The trunnion 124 also carries a second and 30 smaller pinion 132, which is disposed for rotation in accordance with the up-and-down movements of the associated barrier by a rack 134, the supporting arm 136 of which, of adjustable length, is pivotally connected to the barrier by a pin 138 journaled in a boss 140, 40 secured to the barrier's surface by studs 142. A roller guide 144 is rotatably supported adjacent the rack 134 upon a pin 146, which extends from one of the previously mentioned supporting brackets 126. Roller 144 acts to 45 maintain rack 134 in continuous meshing engagement with pinion 132.

With this arrangement, it will be evident that an up or down movement of each barrier 20 effects a corresponding up or down movement 50 of each of the associated links 136, and correspondingly rotates the pinions 132 associated therewith. The rotation of the pinions 132 is amplified by the larger pinions 114 and such amplified motion is transmitted to the associated reflectors 104 through the racks 112 and connecting links 116. Each reflector 104 thus tilts relative to its associated barrier 20 in a manner similar to that described with reference to the reflectors 70. The relation of the parts 60 is such that, as in the previous described modification, the direct beam from each lamp 62 is continuously directed against the associated lens 52 during the up-and-down movement. The reflectors 104, in moving, thus compensate for the 65 change in relative position of the lenses 52 and the lamps 62. In the embodiment now being described, the movements of the reflectors 104, as influenced by the gear train, are continuous in direction and the compensation for the reversal in direction of the horizontal components of movement, described with reference to Figs. 3 and 4, is not provided. With the arrangement of Figs. 5 and 6, accordingly, it is preferred to adjust the mechanism so that the beams of 75

light bear the desired angularity to the highway from the time the barrier reaches the previously described partially elevated or warning position until the fully projected position is reached.

- 5 A somewhat simpler arrangement is illustrated in Fig. 7, in which a reflector 160 is stationarily supported in a barrier 20, adjacent an associated lens 52, by a supporting member 162, one end of which is attached to the barrier forward face.
  - 10 Preferably, reflector 160 is so angled relative to the light source and relative to the lens 52 that when the barrier reaches maximum elevated position, a direct intense beam of light is directed along the roadway substantially parallel thereto.
  - 15 During the initial raising movements, it will be appreciated, light reaching approaching vehicles will be a diffused relatively less intense light. The degree of light transmitted thus constitutes an indication of the degree to which
  - 20 the barrier is elevated.

In a broad sense, the lighting up of the warning signals may be effected in various ways. Preferably it occurs as an incident to the actuation of the barriers, and takes place at or near the beginning of the projecting movement of the barriers. It is preferred also that the warning signals be of the intermittent or flasher type. In many instances, it is found that the warning signals described hereinbefore, and comprising the two warning lights at either end of each barrier, and the illuminated warning letters, are sufficient to constitute the complete signal system. In other instances, it is found desirable to supplement the warning signals thus provided by crossing signals of the general type heretofore in use, and in certain cases to further supplement such signals by the use of bells or similar devices.

40 The remaining two figures, 8 and 9, disclose a preferred control system for actuating the various signal elements associated with the system, Fig. 8 illustrating diagrammatically a preferred track control arrangement which may be used where the barriers are associated with the railroad crossing system, and Fig. 9 showing the various control elements which respond to the track control system and directly effect the lighting of the signals.

Referring first to Fig. 8, the two rails forming a track T_1 are provided with blocks of insulating material 150 , which form a block or track section extending from a point a substantial distance at one side of the crossing to a point a shorter distance on the other side of the crossing. The two rails of track T_2 are similarly divided into a block section of similar extent but disposed in opposite relation to the crossing, it being assumed that traffic on the two tracks travels in the directions indicated by the arrows. The block section associated with track T_1 is provided with a source of track circuit energy illustrated as a conventional battery TB_1 , the terminals of which are connected directly across the two rails of track T_1 , in series with a current limiting resistor R_1 and a conventional switch S_1 . A relay TR_1 is directly connected across the rails of track T_1 adjacent the end of the track section remote from that at which the battery TB_1 is connected. Track section T_2 is similarly provided, with a track relay TR_2 connected across the rails adjacent one end of the track, and a battery TB_2 connected across the rails adjacent the other end of the track, in series with a current limiting resistor and a control switch S_2 .

The switches S_1 and S_2 are continuously closed, as long as the system is in service, and it will be appreciated therefore that track relays TR_1 and TR_2 are continuously supplied with current from their associated batteries TB_1 and TB_2 , the circuits extending through the rails of the associated track sections. 5

As long as no vehicle, effective to form a shunt circuit between the two rails of either section, of lower resistance than the resistances of the relay TR1 and TR2, as the case may be, occupies either section, both relays TR1 and TR2 remain sufficiently energized to hold the contacts TR11 and TR21 thereof in the closed position, in which position they complete an energizing circuit for the coil of a control relay XR, which circuit extends from the positive line conductor through the contacts TR11, TR21, and the coil of relay XR in series, to the negative line conductor. 10 15 20

If a vehicle, effective in accordance with conventional railway signalling practice to form a shunt circuit between the rails of lower resistance than a track relay, enters track section T1 or track section T2, the corresponding track relay TR1 or TR2 is so far de-energized as to release its contact to the open position, interrupting the just described energizing circuit for the control relay **XR**. 25

If the shunting vehicles leave the associated track section, the corresponding track relay TR1 or TR2 again becomes fully energized, and, by reclosing its contact, recompletes the energizing circuit for the control relay XR. It will be appreciated, accordingly, that relay XR responds to the presence in the track sections of vehicles, by assuming the de-energized position, and responds to the departure from the track sections of vehicles by resuming its energized position. It will be appreciated that this is but one of a large number of conventional track circuits, any one of which will accomplish a generally similar result in giving protection to the many varied combinations of train movements.

Referring now particularly to Fig. 9, the control relay XR of Fig. 8 is provided with two normally closed contacts designated $XR1$ and $XR2$ which respectively control the lighting and flasher circuits in the hereinafter described manner. The control system of Fig. 9 also includes a polarized or double coil flasher relay FL , having the contacts $FL1$, $FL2$ and $FL3$. In the de-energized condition of the relay FL , the contacts $FL1$, $FL2$ and $FL3$ occupy either the illustrated positions in which they are in engagement with the left-hand stationary contacts, or opposite positions in engagement with the opposite stationary contacts, depending upon which of the two relay coils a and b is last energized.

The previously identified lamps 62, located in the respective barrier casings, are shown schematically in Fig. 9, and bear the same reference characters as in the corresponding diagram in Fig. 8. The two lamps 62 may be assumed to be associated with one of the barriers at one side of the track and the two lamps 62a may be assumed to be associated with the immediate adjacent barrier at the same side of the track. Two lamps 62A may be assumed to be associated with one of the barriers at the opposite side of the track, and the remaining two lamps 62Aa may be assumed to be associated with the adjacent barrier at such opposite side of the track. As will be evident, the cir- 75

cuits for the just identified lamps are controlled by the flasher relay contacts **FL3** and **FL1**, respectively.

In addition to the flasher lamps just identified, the control system of Fig. 9 provides for the operation of warning bells **170** and **172**, which may be located at the respectively opposite sides of the crossing, and also for traffic lights **174** and **176**, which may also be located at respectively opposite sides of the crossing, as indicated in Fig. 8.

The various relay contacts are shown in Fig. 9 in the positions occupied thereby when the associated coils are de-energized. Normally, however, the control relay **XR** of Fig. 8 remains energized, so that, accordingly, the relay contacts **XR1** and **XR2** of Fig. 9 normally occupy positions opposite to those shown in which the corresponding circuits are open. Normally, accordingly, the circuits for both series of lamps **62**, etc. and for the coils of the flasher relay **FL** are open.

Assuming that a vehicle effective to shunt the track circuits enters either of the track sections identified in Fig. 8, the control relay **XR** becomes de-energized as previously described, permitting the contact **XR1** and **XR2** to move to the positions illustrated in Fig. 9. Closure of contact **XR1** completes circuit for the two series of lamps **62**, etc. as described in detail hereinafter; and also completes the circuit for the traffic lights **174** and **176**. The latter circuit extends from a suitable source of current supply through contact **XR1**, conductor **180**, and through the two lamps **174** and **176** in parallel to an opposite supply terminal. In response to this action, the traffic lights become illuminated and remain so as long as the control relay **XR** remains de-energized.

Closure of contacts **XR2** completes the circuit for the coil **b** of the flasher relay **FL**, which circuit extends from the illustrated positive line conductor through contact **XR2**, relay contact **FL2** and through coil **b** to the negative line conductor. Completion of this circuit causes the flasher relay **FL** to throw the contacts **FL1**, **FL2** and **FL3** to the opposite position into engagement with the right-hand ones of the associated stationary contacts.

This movement of contact **FL2** de-energizes the coil **b**, but completes an energizing circuit for the coil **a**, which circuit is similar to that just traced for coil **b**. The now energized coil **a** throws contact **FL2** to the illustrated position, de-energizing itself, and re-energizing coil **b**. Energization of coil **a** also throws the contacts **FL3** and **FL1** into engagement with the left-hand ones of the stationary contact associated therewith. It is seen, therefore, that closure of contacts **XR2** causes alternate energization and de-energization of the flasher relay coils **a** and **b**, resulting in the contacts **FL3** and **FL1** being vibrated between the right hand and left hand positions thereof. It will be appreciated that the rate of this vibratory action depends entirely upon the design of the relay and may be varied between rather wide limits.

At each engagement of the relay contact **FL1** with the right hand stationary contact, a circuit is completed for one of the lamps **62** and one of the lamps **62a**. The simultaneous engagement of contact **FL3** with the right hand stationary contact completes a circuit for one of the lamps **62A** and one of the lamps **62Aa**. In the right hand position of the relay contacts,

accordingly, one lamp is lighted at each end of each barrier at each side of the intersection.

It is thought to be evident that when the contacts **FL1** and **FL3** engage the left-hand stationary contacts, respectively, circuits are completed for the remaining lamps **62** and **62a** at one side of the intersection, and the remaining lamps **62A** and **62Aa** at the other side of the intersection. The lights at the two ends of each of the barriers at the intersection, therefore, are alternately lighted and extinguished, the light at one end being lighted during the times the light at the other end is extinguished. An effective flasher type signal is thus provided.

It will be noted that the stationary contacts for moving contacts **FL1** and **FL3** are cross-connected, one stationary contact being associated with lights at one side of the crossing and the other stationary contact being associated with lights at the opposite side of the crossing. Thus, even though one or the other moving contacts **FL1** or **FL3** may fall, at least part of the lights at each side of the crossing are effective.

Closure of the control relay contacts **XR2** also completes the circuit for the two warning bells **170** and **172**, which circuit extends from the positive line conductor through contacts **XR2** and thence through the bells **170** and **172** in parallel, to the negative line conductor.

As described in detail in the co-pending application of the present applicant, Serial No. 109,941, filed November 9, 1936, and assigned to the same assignee as the present application, the de-energization of relay **XR** of Fig. 8 also results in initiating the upward movements of the barriers. These upward movements of the barriers are, therefore, accompanied by the energization of the warning lights **62**, etc., the traffic signals **174** and **176**, and the bells **170** and **172** where utilized. The barriers remain in projected position as long as the control relay **XR** remains de-energized, and by reference to Fig. 9, it will be appreciated also that the warning signal system also remains in operation as long as the contacts **XR1** and **XR2** remain closed.

As further described in the just identified co-pending application, the control relay **XR** may become momentarily de-energized, the period of de-energization being insufficient to allow the barriers to reach a fully elevated position. Such momentary periods of de-energization may result, for example, where switching operations are in progress and a vehicle momentarily enters a track section and then retires therefrom. The arrangement of the barriers is such that it is desirable that each barrier, after having initiated an upward movement, complete such upward movement and pass through an entire conventional operating cycle. Similarly, it is desirable to ensure correct signal operation during such operating cycle. To insure the above operation the electrical controllers which constitute parts of the driving system are provided with auxiliary contacts. In Fig. 9, the auxiliary contact associated with the drive unit at one side of the intersection is designated **C5** and the controller contact associated with the drive unit at the other side of the intersection is designated as **C5A**. The controller **180** for actuating the contact **C5** is shown generally in Figure 1, and the operating elements immediately associated with the contact **C5** are shown in Figure 1A.

The controller and the corresponding contacts associated therewith are described in complete detail in the previously identified copending Serial No. 109,941, but for the purposes of the present disclosure it is sufficient to note that the controller 180 is of the drum type, having a rotatable shaft 182, which is driven through a chain 183 in timed relation to the raising and lowering movements of the barrier. As is shown in Figure 1A, the shaft 182 is provided with a cam 184, which is disposed to bear against a contact finger 186, which is supported upon an insulating block 192 associated with the housing. The finger 186 and a corresponding finger 188, stationarily mounted on a block 190, carry the contact elements which are designated C5. The form and disposition of the cam 182 is such that the contacts C5 are maintained in open position when the barrier is in its retracted, or normal, position, but are allowed to close after a slight initial elevating movement of the barrier. The contacts C5 remain closed until, after having reached the fully elevated position, the barrier starts downwardly again towards the retracted position, and the contacts C5, therefore, remain closed so long as the barrier is in the fully elevated position.

As is set forth in detail in the above copending application Serial No. 109,941, the controller 180 is preferably provided with additional contacts which, after being closed as a result of a slight elevating movement of the controller, are effective to maintain the barrier in operation so as to complete the elevating movement thereof and so as to bring about a retracting movement thereof.

The contacts C5 and C5A are shown as connected in parallel with each other and with the control relay contacts XR2. It will be seen, therefore, that even a momentary de-energization of the control relay XR sufficient to cause either of the barriers to move far enough to close the controller contacts C5 and C5A renders these contacts effective to maintain the flasher relay FL and the bells 170 and 172 in operation. After closure of either contact C5 and C5A, accordingly, a re-energization of control relay XR, and a consequent re-opening of contact XR2 is without effect upon the operation of the flasher relay FL, until such time as the barriers reach the maximum elevated position and re-open the contacts C5 and C5A. It will be appreciated that if it is desired to maintain the flasher relay FL in operation until the barriers have resumed a retracted position, the contacts C5 and C5A may be arranged to remain closed until such retracted position is reached.

Each of the barriers is also provided with a limit switch LS, all limit switches at an intersection being connected in parallel with each other and also connected to supply the traffic signals 174 and 176. The limit switches are cross-connected through conductor 180 with contact XR1, and are thus also effective to supply the lamps 62, etc. through the flasher relay contacts. The limit switches LS are arranged to retain the associated contacts normally in an open position, but to close such contacts after a small initial movement of the associated barrier, and retain the contact in the closed position until the barrier has passed through the remainder of its operating cycle and returned to the retracted position. It will be seen that the

limit switch contacts, by being connected directly in parallel with the contact XR1 of the control relay XR, serve to maintain the traffic lights and the flasher lights in operation even though the control relay contacts XR1 re-open. The controller contacts C5 and C5A and the limit switches are thus effective to place the complete signal system in operation in the event any one barrier at an intersection rises even a short distance above the roadway, and to maintain such operation until all barriers are retracted.

The provision of the just-mentioned interlocking action between the signal systems for the several barriers is of particular importance, since, so long as any of the barriers are in any position except the fully retracted position, vehicles approaching the intersection from either side thereof are warned that the barrier system is not in a fully cleared position. With the illustrated system, in which the signal openings for the respective barriers are positioned in the barrier faces, the intensity of the warning light transmitted from a particular barrier towards an oncoming vehicle is, of course, considerably greater when the corresponding barrier is in an elevated position than when such barrier is in the retracted position. It will be noted from Fig. 3, for example, however, that the barrier faces are spaced inwardly somewhat from the front wall of the associated barrier casing 24 so that, even when the barrier is in the fully retracted position, a part of the light transmitted through the corresponding signal openings is by diffusion directed upwardly through the just-mentioned space. The part of the light so diffused upwardly is found in practice to be of sufficient intensity to inform approaching vehicles that the intersection is not in an entirely clear condition. Also, the warning bells 170 and 172 remain in operation until all barriers have returned to their fully retracted positions and thus supplement the effect of the respective signal lights in giving warning to approaching vehicles.

As shown in Figs. 3 and 4, each of the limit switches LS may preferably comprise a housing rigidly secured to the casing of the associated barrier by studs, such as 182A, and having a rotatable contact operating arm 184A which extends outwardly of the casing, and is connected through a link 186A to the associated barrier 20. As will be appreciated, a projecting or retracting movement of the associated barrier thus rotates switch arm 184A in either a clockwise or counter-clockwise direction to thereby correspondingly close or open the associated contacts.

Although specific embodiments of the present invention have been described in detail, it will be appreciated that various changes in the structure and arrangement of the elements may be made within the spirit and scope thereof.

What is claimed is:

1. In a protective system, a barrier of shell construction having a face provided with a signal opening, said barrier being positioned in a highway for pivotal movement about a horizontal axis so as to move the said face of said barrier between a retracted position and a projected position above the level of said highway, a lens positioned in said opening, a stationarily supported source of light for said lens, a reflector carried by said barrier shell for cooperating with said light source and said lens, and means having a part thereof stationarily supported and

having parts connected respectively to said reflector and to said barrier and operated by and in accordance with the movements of said barrier for tilting said reflector relative to said face 5 during a movement of said barrier so as to control the angular relation in a vertical plane between said highway and a beam of light from said source in accordance with the position of the barrier.

10 2. In a protective system, a barrier positioned in a highway for pivotal movement about a horizontal axis so as to move a face of said barrier between a retracted position and a projected position above the level of said highway, said 15 face of said barrier having a signal opening, a lens positioned in said opening, a stationarily supported source of light for said lens, a reflector carried by said barrier for cooperating with said light source and said lens, means for pivotally supporting said reflector upon said barrier, an arm connected to said reflector, and 10 means including a gear train having a stationarily supported part and connected between said arm and said barrier for tilting said reflector relative to said barrier during the movement of said barrier, so as to control the angular relation in a vertical plane between the highway 15 and a beam of light from said source.

15 3. In a protective system, a barrier positioned in a highway for pivotal movement about a horizontal axis so as to move a face of said barrier between a retracted position and a projected position above the level of said highway, said 20 face of said barrier having a signal opening, a lens positioned in said opening, a stationarily supported source of light for said lens, a reflector carried by said barrier for cooperating with said light source and said lens, means for pivotally supporting said reflector upon said barrier, and means including a cam member and a cam track member for tilting said reflector relative to said barrier so as to control the angular relation in a vertical plane between the highway 25 and a beam of light from said source in accordance with the movement of said barrier, one of said members being stationarily supported and the other member being connected to the reflector.

30 3. In a protective system, a barrier positioned in a highway for pivotal movement about

a horizontal axis so as to move a face of said barrier between a retracted position and a projected position above the level of said highway, said face of said barrier having a signal opening, a lens positioned in said opening, a stationarily supported source of light for said lens, a reflector carried by said barrier for cooperating with said light source and said lens, means for pivotally supporting said reflector upon said barrier, an arm connected to said reflector, and 10 means including a gear train having a stationarily supported part and connected between said arm and said barrier for tilting said reflector relative to said barrier during the movement of said barrier, so as to control the angular relation in a vertical plane between the highway 15 and a beam of light from said source.

4. In a protective system for an intersection having a plurality of barriers positioned at respectively opposite sides of said intersection, each 20 whereof is movable between a retracted position in which it does not interfere with travel thereover of vehicles and a projected position in the path of such travel, an electrically responsive signal element individual to each of said 25 barriers, and means including circuit connections and switch mechanism responsive to a predetermined projected position of any of said barriers for controlling the said signal elements for all of said barriers.

30 JAMES MOORE EVANS.
